UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

WATCHCASE.

SPECIFICATION forming part of Letters Patent No. 787,637, dated April 18, 1905.

Application filed April 16, 1904. Serial No. 203,455.

To all whom it may concern:

Be it known that I, WILSON E. PORTER, a citizen of the United States, residing at New Haven, in the county of New Haven and State of Connecticut, have invented a new and useful Improvement in Watches; and I do hereby declare the following, when taken in connection with the accompanying drawings and the figures of reference marked thereon, to be a full, clear, and exact description of the same, and which said drawings constitute part of this specification, and represent, in—

Figure 1, a front view of a watch constructed in accordance with my invention; Fig. 2, an edge view thereof; Fig. 3, a rear view thereof; Fig. 4, a broken rear view of the watch with the case-back removed to show the inside cap made integral with the case-center; Fig. 5, a detached rear view of the watch-movement; Fig. 6, an enlarged broken sectional view of the watch on the line *a b* of Fig. 4; Fig. 7, a detached perspective view of the movement-support.

My invention relates to an improvement in watches, the object being to save time, labor, and expense in fitting a watch-movement in its case, to secure it accurately and solidly in place, and to eliminate the danger of binding or springing it or the case so as to interfere with its performance.

With these ends in view my invention consists in a watch having certain details of construction and combinations of parts, as will be hereinafter described, and pointed out in the claims.

In carrying out my invention as herein shown I employ a movement-support in the form of a ring 2, embracing the rear movement-plate 3, bearing at its forward edge against the inner face of the edge of the front movement-plate 4 and made wide enough to project at its rear edge beyond the rear or outer face of the said rear movement-plate 3, so as to form, in effect, a supporting-foot 2^a, as shown by Fig. 6. As shown, the said ring is broken away at the top; but it may be made continuous, if desired. The case-body or case-center comprises a hollow ring 7, an inside cap 8, made integral with the back of the said

ring, and a circular bezel-receiving flange 9, 50 made integral with the front of the said ring and turned inwardly into the plane thereof and forming an opening large enough to permit the watch-movement to be passed through it into the body of the ring. The bezel 10 is 55 snapped over the flange 9 and carries the watch-crystal 11. A case-back or outside cap 8^a, formed with an inwardly-turned flange in the usual manner, is snapped over the shoulder 8^b at the junction of the inside cap 8 with 60 the ring 7, as shown in Fig. 6. It will be understood, of course, that the movement is made sufficiently small in diameter to be introduced into the ring 7 through the said flange 9 at the front thereof. 65

To secure the movement in place within the ring 7, I employ anchor-screws 12, passing from rear to front through holes 13 in the inside cap 8, through registering holes 14 in the rear movement-plate 3, and entering threaded 70 screw-holes 15, formed in the front movement or pillar plate 4, the said anchor-screws being located within the movement-support 2. When the said screws 12 are turned home, they will draw the entire movement rearward, 75 so as to seat the edge of its front movement-plate 4 upon the forward edge of the said movement-support 2 and in turn draw the movement-support rearward, so as to seat its rear edge or foot 2^a throughout the length 80 thereof upon the inner face of the inside cap 8 of the ring 7. The said foot 2^a holds the rear movement-plate 4 away from the inside cap 8 sufficiently to provide an ample clearance-space 16 for the bridge 17, which carries 85 the regulator-lever 18. The watch-movement is also provided with the usual dial-plate 19, to which the dial 20 is applied.

By means of my improved construction I save the time, labor, and expense of "fitting" 90 the movement in the case, and as the entire rear edge of the ring 2 bears upon the inside cap 8 I secure a solid support for the movement within the case. Moreover, I avoid springing the rear movement-plate, which is 95 lighter than the front movement-plate, which takes the draft or strain of the screws, none of which falls upon the rear movement-plate.

Furthermore, the entire draft of the screws falls upon the back of the case-center—on the one hand, where engaged by the screw-heads and, on the other hand, where engaged by the rear edge of the ring 2—whereas commonly the draft of the screws is both at the back and front of the case-center and tends to draw the same together and distort its shape with the danger of binding the movement.

10. It is apparent that in carrying out my invention some changes from the construction herein shown and described may be made. I would therefore have it understood that I do not limit myself thereto, but hold myself at 15 liberty to make such departures therefrom as fairly fall within the spirit and scope of my invention.

Having fully described my invention, what I claim as new, and desire to secure by Letters 20 Patent, is—

1. In a watch, the combination with a case-center having an inside cap, of a watch-movement made sufficiently small to be set into the said case-center from the front thereof, a movement-support resting upon the said cap, one or more anchor-screws passing from rear to front through the said inside cap and screwing into the front plate of the said movement and coacting with the said cap to draw the 25 movement rearward and seat its front plate firmly upon the said support and in turn to draw the said support rearward and seat the same firmly upon the said cap; and a case-back or outside cap fitted over the case-center to cover the said inside cap.

2. In a watch, the combination with a case-center having an integral inside cap, of a watch-movement made sufficiently small to be set into the said case-center from the front thereof, a movement-support resting upon the said cap and forming a seat for the said movement, and one or more screws passing from rear to front through the said cap, entering the said movement and coacting with the said cap to draw the said movement rearward and seat 45

the same firmly upon the said movement-support and in turn to draw the said movement-support rearward and seat the same firmly upon the said cap.

3. In a watch, the combination with a case-center having an integral inside cap, of a watch-movement made sufficiently small to be set into the said case-center from the front thereof, a ring forming a support for the said watch-movement and encircling and projecting rearward beyond the rear plate thereof, and anchor-screws passing from rear to front through the said cap into the front plate of the said movement and coacting with the said cap to draw the movement rearward so as to seat the same upon the said ring, and in turn to draw the said movement-support rearward and seat the projecting rear edge thereof on the inner face of the said cap.

4. In a watch, the combination with a case-center having an integral inside cap, of a watch-movement made sufficiently small to be set into the said case-center from the front thereof, a ring encircling and projecting rearward beyond the rear plate of the said watch-movement, and at its forward edge extending under and forming a bearing for the front plate of the said movement, and anchor-screws passing from front to rear through the said inside cap and through the said rear plate and inside of the said ring and screwing into the said front plate and coacting with the said cap to draw the said movement rearward so as to seat its front plate upon the forward edge of the said ring, and in turn to draw the said movement-support rearward and seat its projecting rear edge upon the inner face of the said cap.

In testimony whereof I have signed this specification in the presence of two subscribing witnesses.

WILSON E. PORTER.
